UNITED STATES PATENT OFFICE.

GILBERT LLOYD ADAMS, OF ALTOONA, PENNSYLVANIA.

CAR-BRAKE.

SPECIFICATION forming part of Letters Patent No. 347,911, dated August 24, 1886.

Application filed February 8, 1886. Serial No. 191,161. (No model.)

To all whom it may concern:

Be it known that I, GILBERT LLOYD ADAMS, of Altoona, in the county of Blair and State of Pennsylvania, have invented a new and useful Improvement in Car-Brakes; and I hereby declare the following to be a full and clear description thereof.

This invention relates to an improved operating mechanism for the car-brake described and claimed by me in Patent No. 326,191, of September 15, 1885.

The specific invention relates to improvements in the coupling attachments for the contiguous ends of the operating levers by means of plates in lieu of rings and links, thus securing the said levers from dropping down by accident, and also to an improved device for coupling the actuating-lever to the operating-levers, by means of which improvement I am able to dispense with one of the actuating-levers I formerly employed.

The invention will be readily understood by reference to the accompanying drawings, of which—

25 Figure 1 is a general plan of a car-truck, showing the improved brake attachments. Fig. 2 is a longitudinal sectional elevation of the same. Figs. 3, 4, and 5 are detail drawings of brake parts.

30 The truck shown has the ordinary freight-car construction, showing a bolster, A, and a spring-bar beam, A'. To the sides of the beam A', near its bottom edge, is secured a fulcrum-block, D—one on each side of the beam, thus forming a pair—and each end of the beam carries a similar pair, thus forming suitable fulerums for four operating-levers, G, the lower end of each of which carries a brake, H, as in my former patent above alluded to.

40 The longer ends of the operating-levers are engaged with and moved by a single actuating-lever, E, in lieu of a pair of such levers, as in my said former patent. The contiguous ends of each pair of the said operating-levers are coupled to a central transverse plate, I, respectively, by a link-plate or pair of link-plates, I', as shown clearly in Fig. 1, thus obviating the liability of either of the levers dropping down so as to endanger serious ac-

ident to the train in case of any breakage of the links or rings shown for the connection of these levers in my said former patent, for in this improvement the parts I, I', and G constitute a mutual vertical support or rest, each for the other, in case of the breakage of any one of the said parts. The said levers G and their coupling-links I' and the central plate, I, are respectively coupled together by cylindrical keyed pins i i' , so as to allow the said parts free lateral play, the one upon the other.

To the central parts of each of the central plates, I, and secured thereto by an assembling-pin, i' , similar to those above described, are connected, respectively, on the opposite sides of the bolster A, a rod or draw-bar, K, and a clevis-bar, K'. In the inner end of the bar K' is secured a grooved sheave, K², by means of an assembling-pin, k , on which the said sheave is allowed to freely revolve. The draw-bar K is on a line with the clevis-bar K', to which it extends only a part of the distance, and a chain or wire rope, K³, is attached to the free end of the said bar K, and extends thence to and around the sheave K², and has its other end secured to the draw-bar K', by means of which it is attached to the actuating-lever E. This lever E is operated in the usual manner by means of a brake-wheel or in any other desired method of applying 80 car-brakes.

It is obvious that by moving the operative end of the lever E in the proper manner the rod K' will draw the chain or wire rope over the sheave K² and along with it the draw-bar K toward the said sheave, thus forming and uniting the levers E and G into a set of compound levers, by means of which the brakes H are applied to the wheels of the car with very great power and effect.

Having thus described my invention, what I claim as new, and desire to secure by Letters Patent, is—

1. The operating-levers G, the links or plates I and I', and the actuating-lever draw-bars K K', combined and arranged substantially as described.

2. The operating-levers G, actuated by a

single actuating lever, E, through the connecting draw-rods K and K', the connecting chain or wire rope operating over a sheave, K², journaled in the free end of one of the said draw-rods and attached to the actuating-lever by the draw or connecting rod K⁴, the whole combined and arranged substantially as described.

In witness whereof I hereunto set my hand in presence of two witnesses.

GILBERT LLOYD ADAMS.
